UNITED STATES PATENT OFFICE.

FREDERICK A. HART, OF JERSEY CITY, NEW JERSEY, ASSIGNOR TO UNDERWOOD COMPUTING MACHINE COMPANY, OF NEW YORK, N.Y., A CORPORATION OF NEW YORK.

COMBINED TYPE-WRITING AND COMPUTING MACHINE.

1,237,899.

Specification of Letters Patent. Patented Aug. 21, 1917.

Application filed September 20, 1911. Serial No. 650,422.

To all whom it may concern:

Be it known that I, FREDERICK A. HART, a citizen of the United States, residing in Jersey City, in the county of Hudson and State of New Jersey, have invented certain new and useful Improvements in Combined Type-Writing and Computing Machines, of which the following is a specification.

My invention relates to automatically controlled devices for operating combined type-writing and computing machines. It is illustrated as attached to a machine of the Underwood-Hanson type.

Among the objects of my invention are the automatic covering of the figure keys and the totalizer, the automatic starting of a drive for the computing mechanism and the automatic releasing of said covering devices, (hereinafter called locking devices). Other objects will be pointed out in the specification or be obvious to those skilled in the art. One result is that it will be impossible to strike a numeral key or take a total off the totalizer while the computing mechanism is being driven by power, another result is that the motor takes power only when the computing machine actually requires to be driven, thus avoiding continual waste of power at other times.

The preferred form of structure here shown in detail comprises a dog operating two links, one of which operates the key-locking or silencing mechanism, while the other operates the releasing mechanism by closing an electric circuit around a magnet, thus moving an electric switch to start a motor and throw in a clutch between the motor and the operating mechanism. This motor drives the adding machine, positively releases the silencing or locking devices, and sets the mechanism ready to write and compute a new number as soon as the carriage is shifted. Certain features of my invention are applicable to other types of machines.

While I have shown the silencing device for the keys in the form of a bar which interferes with their ready operation, it is obvious that for some of the purposes of my invention, other forms of silencing means might be used.

In the accompanying drawings,

Figure 1 is a sectional elevation of an Underwood-Hanson combined typewriting and

adding machine, of the kind to which the above improvements are applied.

55

Fig. 2 is a front elevation, partly in section, of the electro magnet, the motor, and the connections between them.

Fig. 3 is a diagrammatic view of the electro-magnet and the contacts for starting it. 60

Fig. 4 is an enlarged view of the electric contacts.

Fig. 5 is an enlarged plan view of the shifting device operated by the carriage.

Fig. 6 is a section through the switch and clutch of the motor when at rest. 65

Fig. 7 is a section through the same at the moment of starting.

Fig. 8 is a perspective view of a disk, used for supporting and operating a rotary bridge. 70

Fig. 9 is a side elevation of a pair of brushes and the device on which they are mounted.

Fig. 10 is an elevation of the clutch cup 75 shaped ring.

Fig. 11 is a fragmentary section showing the ends of the jacks and the tappet for raising them.

Numeral keys 1 depress levers 2 to operate 80 through bell cranks 3 to throw type bars 4 upwardly and rearwardly to strike on the front of platen 5, which is mounted to travel with a letter-feeding carriage 6, driven in the usual manner by a spring (not shown). 85 This carriage 6 is controlled by letter-feeding devices comprising a universal bar 7 actuated by heels 8 on the type bars 4, and forming part of a frame 9, which has vibrating supports 10, and actuates the usual letter feeding dogs 11 to control escapement wheel 12.

85

Upon said carriage 6 is a denominational selector in the form of a tappet or dog 13, which is usually adjustable along the rack 95 bar 14, and has a cam edge to lift successively jacks 15 arranged in a row, mounted on a fulcrum 16. The rear ends 17 of the jacks press down links 18, to vibrate levers 19, which are connected to linkages 20 to 100 elevate the rear ends of a series of bars 21, whose forward ends carry racks 22, meshing with pinions 23 fixed on dial or computing wheels 24, whereby the latter may be rotated.

105

The numeral keys 1 have stems 25, to op-

erate arms 26 fast upon shafts 27, which support linkages 28 on arms 29. These linkages are depressed when arms 26 are depressed, and are adapted to strike any one of a series of pins 30 upon the elevated rack bar 21. As the carriage 6 feeds step-by-step, the rack bars 21 are elevated in succession, and downwardly from each is projected a pin 30 in the manner just described. The 10 rack bars fall to normal position, thus bringing the depressed pins into the path of a cross bar 31 forming part of a general operator. The general operator, which also comprises a pair of arms 32 and a pair of 15 racks 33 on opposite sides of the machine, is connected by pinions 34 and segments 35 to a shaft 36. After the pins are set up (i. e., depressed) by the numeral keys 1, the general operator moves forward, and the bar 20 31 of the general operator engages all the depressed pins and drives forward the racks 22 corresponding distances, to turn the dial wheels 24 accordingly. The wheels are not turned on the return stroke, because of a 25 pawl and ratchet connection not shown, but the pins are restored in their original positions ready to set up for a new number.

To drive the machine by power, an intermittently operated motor 37 is attached to 30 the adding machine table 39, and is provided with a main shaft 40. Upon shaft 40 is fixed worm 41 turning worm wheel 42 mounted to revolve on shaft 43. Arm 44, (Figs. 1 and 2) fast on shaft 43, carries slide 45 mounted 35 in bar 46. Thus when the motor 37 turns worm 41 and worm wheel 42, if shaft 43 rotates with wheel 42 arm 44 will rotate about shaft 43, reciprocating bar 46, on which rests yoke 47 bolted to the rack 33 of the 40 general operator and drives it.

Key 48 on plunger 49 depresses bar 50 (Fig. 2) to strike the end 51 of lever 52 to raise pin 53, which controls the clutch and starting switch of motor 37.

Referring now particularly to Figs. 2, 6, 45 7, 8, 9 and 10, pin 53 extends normally through casing 54, so as to press arm 55 against shoulder 56 of ring 57 compressing spring 59. Ring 57 is not fixed to hub 60 of worm wheel 42, but engages it with some friction obtained by blocks 61 pressed against 60 by springs 62 mounted on 57 by screw 63. Within sockets 64, of ring 57, rolls 64^a turn freely and are normally out of 55 contact with cup member 65 fixed on shaft 43 by key 66. Cup member 65 has coarctate or cam sockets 67 to insure this freedom from contact, but if hub 60 turns counter clockwise slightly, it carries ring 57 and rolls 64^a to the shallow part of the socket 67 and they jam, thus forcing ring 65 and hub 60 to revolve together, and the combination forms a clutch driving shaft 43 from worm wheel 42.

65 Arm 55 is formed as a turned up edge of

ring 68 loose on cup member 65. On ring 68 is mounted the conductor ring 69, constituting a rotary bridge having a gap filled by insulation segment 70. Against this ring bear the ends 71 and 72 of brushes 73 and 74 mounted on an insulator plate 75 fixed on stud 76 of the casing. Through these brushes the current driving the motor passes from wires 77. There will then be one position of the brushes in which end 71 of brush 73 will bear on the insulator segment 70. In this position, the motor will not be driven, and the parts are so arranged that this is the case when pin 53 is holding arm 55, as shown in Fig. 6. To start the motor 80 the brushes and insulator segment 70 are so set that the withdrawal of pin 53, as shown in Fig. 7, will bring the conductor part of ring 70 over brush 73, thus sending the current through the motor. This carries ring 85 57 around as above described till the rolls jam, and then the whole clutch revolves.

In actual operation pin 53 is dropped back immediately by the pressure of spring 78 mounted on the main frame and pressing 90 lever 52. The motor continues to drive the machine till arm 55 strikes pin 53, when ring 57 is arrested and rolls 64^a no longer bind. Shaft 43 accordingly stops, and current ceases to pass through the motor, 95 though the momentum may keep it revolving independently for a time.

To effect the automatic starting of the motor the following mechanism is used. Fig. 5 is an enlarged plan showing the frame 100 79 carrying the jacks 15. The last jack to the left bears on a link 18 which extends downward like the other links 18 above described, but carries a lug 80 carrying a pin which rests in fork 81 of bell crank 82, the 105 other end 83 of which carries a spring 84 extending from the main frame, and tending to draw link 18 upward. Beneath the boss of lever 82 is a pin 85 of insulating material resting on electric spring terminal 86 110 and adapted to press it against another terminal 87 and thus close a leading circuit (see Figs. 3 and 4). A circuit wire 88 is connected to terminals 86 and 87 by suitable binding keys and leads to the windings 88^a 115 of an electro-magnet supported from the main frame by a U-shaped member 89 held to its yoke by screws 90. Above the cores 91 of the magnet is an armature 92 attached by screws 93 to lever 52 from which the starting pin 53 is hung. Also included in the electro-magnet leading circuit is preferably included a battery 94, which may consist of a few dry cells to furnish a low tension current which will not spark.

It will be evident that when the dog 13 is moved along with the typewriter carriage past the jack, for the last or units column of figures, it will strike the last jack and depress the pin 85 to close the leading circuit 120 125 130

around the magnet. This will draw the armature down, raise the starting pin, and the motor in the main circuit will drive the worm wheel till one stroke of the general 5 operator is finished, thus adding in the numerals just written, and restoring the pins ready to be set for a new number.

Special jack 15 is cut away at 95, Fig. 11, so that it is not held raised, but is only 10 raised momentarily as the carriage in its letter-spacing movement carries the tappet 13 from one position of rest to the next. Thus the link 18 closes the leading circuit 15 just long enough to energize the magnet and thus raise the starting pin. Fig. 11 shows the position of the parts after passing the units jack and striking the special jack.

A bar or guard 96 is provided for obstructing the operation of the numeral keys 20 1, and a shutter 97 for covering the totalizer 24. Bar 96 is fixed on rods 98 so that it may readily swing from normal (shown in dotted lines) to covering position, and these rods are fast on rock shaft 99. Shutter 97 is 25 rotated by rod 100, the latter pivoted to 97 at 101 and to lever 102 at 103. Lever 102 is fast on said rock shaft 99, so that the shutter 97 and bar 96 move simultaneously.

Operating arm 104 is normally drawn 30 down to swing the bar free of the keys and the shutter from the totalizer. It is locked in this position against the tension of spring 105, by slideable latch 106, the point 107 of which is adapted to rest in notch 108 of said 35 operating arm.

After a numeral has been written in the units column, the carriage 6 moves on one step (to the Fig. 11 position) and the tappet 13 momentarily raises the special jack 15 40 and thereby depresses link 18 to act through bell crank 109 to draw back said latch 106 from notch 108 to release operating arm 104 and permit spring 105 to operate. A guide pin 110 is provided for latch 106.

45 The connection between spring 105 and operating arm 104 includes a bell crank 111 which raises fork 112, in which rests pin 113* on a projection of said operating arm.

The general operator depresses operating 50 arm 104 by means of a bell crank 113, which has one arm 114 resting in a notch 115 in the side frame 33 of said general operator. The forward movement of the general operator causes this arm 114 to ride up onto the 55 flat side 116 of said side frame 33, and swings arm 117 of said bell crank 113 against an arm 118 of bell crank 111. This raises said arm 118 and depresses operating arm 104 so that slideable latch 106 may be driven 60 into notch 108 by spring 119 on shaft 120 and relock the key guard and totalizer shutter in inoperative position.

65 The operation of the machine is as follows: The operator depresses numeral keys printing numbers and recording them in the

computing device in the various columns till one is struck in the units column. After passing this the tappet on the carriage, which has successively depressed the jacks for each column to control the computing 70 mechanism, momentarily depresses the special jack. This moves one link to lock the numeral keys and the totalizer, while the other raises the starting pin, sending current through the motor to drive the computing mechanism by the clutch. This automatically releases the locking devices, and when the general operator has completed one full movement, the clutch releases itself and 75 breaks the current.

80 Where in the specification and in the claims, I have used the term "silencing device" or "silencing means," it is to be understood that I refer to the fact that the setting-up of the indexing devices by operating the 85 keys in the usual manner is discontinued, and I do not limit myself to the particular form of construction shown. Any form of device by which the function of the keys for controlling the setting of digits is interfered with or rendered quiescent, or put at rest, or held in abeyance, is within the scope 90 of the term "silencing."

95 Variations may be resorted to within the scope of the invention, and portions of the improvements may be used without others.

Having thus described my invention, I claim:

1. The combination with a computing 100 mechanism acting through a cycle of operation, of indexing devices for controlling said computing mechanism during a setting-up portion of said cycle, means for silencing the indexing devices when they have completely set up a number, and means for rendering said silencing means ineffective, including a motor and a circuit to said motor automatically closed when said indexing devices have been completely set up.

2. The combination with a computing 110 mechanism acting through a cycle of operation, of indexing devices for controlling the computing mechanism during a setting-up portion of said cycle, mechanism for automatically preventing a continuation of the 115 cycle of operation when said indexing devices have completely set up a number, means for rendering said preventing means ineffective, and a motor, controlling said means, brought into play automatically 120 when said indexing devices have been completely set up.

3. The combination with a computing 125 mechanism, of indexing devices for controlling the action of said computing mechanism, means for silencing said indexing devices, coming into play automatically at the conclusion of the indexing operation, and driving means brought into play automatically 130 at the same time as said first-mentioned

means for operating said computing mechanism and rendering said first-mentioned means ineffective.

4. The combination with computing mechanism, of means for initiating a computing action of said computing mechanism, said computing mechanism including a series of devices and members controlling said devices in which numbers may be temporarily registered, silencing means for said initiating means coming into play automatically at the completion of the registering of a number, a motor, and controlling means coming into play automatically at substantially the same time as said silencing means for driving said computing mechanism to carry numbers from said members into said devices, and also for rendering ineffective said silencing means.

10 5. The combination with a computing mechanism, of a series of numeral keys for controlling the action of said computing mechanism, a series of jacks for controlling said computing mechanism, a special jack, a tappet operating said jacks successively, a silencing device for said numeral keys controlled by said special jack, and a computing-mechanism drive and means for rendering said silencing device again active, also controlled by said special jack.

6. The combination with a computing mechanism, of a series of numeral keys for controlling the action of said computing mechanism, a series of jacks for governing the action of said computing mechanism, a special jack, a tappet operating said jacks successively, a silencing device for said numeral keys controlled by said special jack, and retiring means for said silencing device also controlled by said special jack.

7. A computing machine having setting-up mechanism and computing mechanism, a series of jacks controlling said computing mechanism, a special jack, a silencing device for said setting-up mechanism controlled by said jack, a link operated by said jack, an electric circuit controlled by said link, a motor, a device for controlling the starting of said motor controlled by said circuit, and a general operator driven from said motor to render said silencing device ineffective, and operating said computing mechanism.

8. A combined typewriting and computing machine having a traveling carriage and a computing mechanism, said computing mechanism having a cycle of operation comprising a setting-up portion and an operating portion; and comprising, in combination, means for silencing said setting-up portion, means for controlling said operating portion, and means under control of said traveling carriage for concomitantly calling into action both said silencing means and said operation-controlling means.

65 9. A computing machine having a travel-

ing carriage, computing devices, indexing devices which are preliminarily set to represent a number, and a general operator for carrying into the computing devices the number set by said indexing devices; and comprising, in combination, means for initiating the movement of the general operator, and means for silencing said indexing devices until the general operator has completed its work of carrying numbers into the computing devices and comprising a jack controlled from said carriage, and means controlled by said jack for bringing into action both said means.

10. In a key-controlled computing mechanism, a carriage, step-by-step feeding means for said carriage, type-bars for writing on paper carried by the carriage, a computing device, keys controlling said computing device, said type-bars and said step-by-step feeding means, a series of jacks, one for each column of numerals registered by the computing device, a special jack next to the units column jack, means on the carriage to operate said jacks successively by the step-by-step feeding motion, a member moved by said special jack to silence said keys, and a member also moved by said special jack to operate said computing device, and to render ineffective said silencing member.

11. In a key controlled computing mechanism, a carriage adapted to carry a sheet to be written on, type bars, keys controlling and operating the type bars, means on the carriage for momentarily closing a leading circuit and silencing said keys, and means controlled by the leading circuit to drive the computing mechanism and release said keys.

12. In a combined typewriting and computing machine, the combination with computing wheels and numeral keys, of members in which numbers are temporarily registered, a motor for carrying numbers from said members into said wheels, a selector on said carriage for selecting said members *seriatim* to register numbers on them, and means moved by said selector for silencing said keys and starting said motor.

13. In a combined typewriting and computing machine, the combination with computing wheels and numeral keys, of members in which numbers are temporarily registered, a motor for carrying numbers from said members into said wheels, a selector on said carriage for selecting said members *seriatim* to register numbers on them, a cover for said wheels, and means moved by said selector for covering said wheels, starting said motor, and uncovering said wheels by said motor.

14. In a combined typewriting and computing machine, the combination with computing wheels and numeral keys, of members

- in which numbers are temporarily registered, a motor for carrying numbers from said members into said wheels, a selector on said carriage for selecting said members *seriatim* to record numbers on them; means for covering said wheels and locking said keys, and means moved by said selector for making said cover and lock effective, and for unlocking and uncovering said keys and wheels by the operation of said motor. 10
15. In a combined typewriting and computing machine, the combination with a denominational selector, of a series of identical jacks moved *seriatim* by said selector, a jack having a face half the width of said identical jacks, an extension on said jack to double its width, and two links moved by said double width. 15
16. In a combined typewriting and computing machine, the combination with computing wheels and numeral keys, of members in which numbers are temporarily registered, a motor for carrying numbers from said members into said wheels, a selector 20 on said carriage for selecting said members *seriatim* to register numbers on them, a series of jacks by which said members are selected, an electric circuit, and a jack for closing said circuit momentarily to cause said motor to carry numbers from said members to said wheels and to silence said keys, said motor rendering said keys again effective. 30
17. In a combined typewriting and computing machine, the combination with computing wheels and numeral keys, of members in which numbers are temporarily registered, a motor for carrying numbers from said members into said wheels, a selector on 35 said carriage for selecting said members *seriatim* to register numbers on them, a series of jacks by which said members are selected, another jack, a link extending from said jack to operate a silencing device for said keys, and a shutter for said wheels, a link extending from said jack to control the starting of said motor, and means operated by said motor to render said silencing device ineffective and remove said shutter 45 from said wheels. 50
18. The combination with a computing mechanism, of a series of numeral keys for controlling the action of said computing mechanism, silencing means for said numeral keys, a motor for driving said computing mechanism, and a single jack for controlling both the action of said motor and the action of said silencing means. 55
19. The combination with a computing mechanism, of a traveling member controlling a computing zone for said computing mechanism, a series of numeral keys for controlling the action of said computing mechanism, a motor for driving said computing mechanism, silencing means for said 60
- keys, and means operated at the end of a computing zone by said traveling member to actuate said silencing means and to enable said motor to drive said computing mechanism. 70
20. The combination with a computing mechanism, of a traveling member controlling a computing zone for said computing mechanism, a series of numeral keys for controlling the action of said computing mechanism, a motor for driving said computing mechanism, silencing means for said keys, means operated at the end of a computing zone by said traveling member to actuate said silencing means and to enable said motor to drive said computing mechanism, and releasing means for said silencing means driven by said motor at the driving of said computing mechanism. 75
21. The combination with a computing mechanism, of a series of numeral keys for controlling the action of said computing mechanism, traveling means for controlling the computing zone of said computing mechanism, a motor for driving said computing mechanism to run up a computation, means coming into play at the end of a computing zone as determined by said traveling means for enabling said motor to drive said computing mechanism to run up the number of the computing zone, and silencing means for said keys also coming into play at the end of the computing zone. 80
22. In a computing device, a jack broadened at one end to increase the scope of its action, and doubly narrowed at its opposite end to shorten the period of its action. 100
23. The combination with a computing mechanism, of a motor for driving said computing mechanism, numeral keys for controlling the action of said computing mechanism, a traveling tappet connected to control the denominations of said computing mechanism, a trip for said motor, silencing means for said keys, and a single jack operated by said tappet at the end of a computing zone for concomitantly actuating said silencing means and said trip. 105
24. A combined typewriting and computing machine having a traveling carriage and a computing mechanism, said computing mechanism having a cycle of operation comprising a setting-up portion and an operating portion; and comprising, in combination, means for initiating the operating portion of the cycle, means for silencing said setting-up portion until said operating portion is completed, both said means being under the control of said traveling carriage, and means brought into action during the operating portion of said cycle to render said silencing means ineffective. 115
25. The combination with a computing mechanism, of a series of jacks connected to control the action of said computing mechanism, silencing means for said 120
- 125
- 130

anism, numeral keys controlling the actuation of said computing mechanism, a motor for driving said computing mechanism, silencing means for said keys, a traveling element operating said jacks successively, and means controlled by the last jack in the series for concomitantly enabling the drive of said computing mechanism by said motor and causing a coming into play of said 10 silencing means.

26. The combination with a computing mechanism, of a series of jacks connected to control the action of said computing mechanism, numeral keys controlling the actuation of said computing mechanism, a motor for driving said computing means, silencing means for said keys, a traveling element operating said jacks successively, and means controlled by the last jack in the series for 15 concomitantly enabling the drive of said computing mechanism by said motor and causing a coming into play of said silencing means, said silencing means remaining in action in case said motor fails to drive said 20 computing mechanism completely, and being released on the driving of said computing mechanism by said motor.

27. The combination with a plurality of computing wheels, of valuating mechanism 30 for accumulating digit by digit, a number to be run into said computing wheels, driving means for running the number after accumulation into said computing wheels, numeral keys for controlling the accumulation 35 of the digits, all of said parts comprising a computing mechanism, guarding means for silencing the functions of said computing mechanism when all of the digits of a number to be run up into said computing wheels 40 have been accumulated prior to their transfer to said computing wheels, and means coming into play automatically at the completion of the accumulation of the digits of a number to be computed, to cause an actuation 45 of said driving means to run the accumulated digits concomitantly into said computing wheels, and at the termination of such action to silence said guarding means so as to permit further functioning of said 50 computing mechanism.

28. A computing machine having a traveling carriage, computing devices, indexing devices which are preliminarily set to represent a number, and a general operator for 55 carrying into the computing devices the number set by said indexing devices; and comprising, in combination, means controlled by said carriage for initiating the movement of the general operator, and for 60 silencing said indexing devices until the general operator has completed its work of carrying numbers into the computing devices.

29. A combined typewriting and computing machine having a traveling carriage 65

and computing mechanism, keys for writing a number digit by digit, and a general operator for carrying the number set by the keys into the computing mechanism; and comprising, in combination, means controlled by the carriage on writing the digit in the units column for initiating the movement of the general operator and for silencing the numeral keys until the general operator has completed its work of carrying 70 numbers into the computing mechanism. 75

30. A computing machine having a traveling carriage, computing devices, indexing devices which are preliminarily set to represent a number, and a general operator for carrying into the computing devices the number set by said indexing devices; and comprising, in combination, means for initiating the movement of the general operator, and means for silencing said indexing 80 devices until the general operator has completed its work of carrying numbers into the computing devices, and comprising a jack controlled from said carriage, and means controlled by said jack for directly 85 bringing said silencing means into play at the initiation of the movement of the general operator and indirectly rendering the same ineffective at the conclusion of the 90 movement of the general operator. 95

31. A computing machine having a traveling carriage, computing devices, indexing devices which are preliminarily set to represent a number, and a general operator for carrying into the computing devices the number set by said indexing devices; and comprising, in combination, means for initiating the movement of the general operator, and means for silencing said indexing 100 devices until the general operator has completed its work of carrying numbers into the computing devices, and comprising a jack controlled from said carriage, and means controlled by said jack for directly 105 bringing said silencing means into play at the initiation of the movement of the general operator and indirectly rendering the same ineffective through the medium 110 of the general operator. 115

32. In a combined typewriting and computing machine, the combination with a computing mechanism, of a series of indexing devices, each one of which may control the computing mechanism in any denomination thereof, operating means for carrying 120 into the computing mechanism numbers as indexed by said devices, and means for silencing said indexing devices and concomitantly bringing into action said operating means. 125

33. In a combined typewriting and computing machine, the combination with numeral keys and computing wheels, of members in which numbers are temporarily registered as written, a general operator for 130

- carrying numbers from said members into said wheels, a traveling carriage, a denominational selector on said carriage, a jack moved momentarily by said denominational selector to obstruct the operation of said keys, and an extension on said jack acting automatically during a computing operation to cause the operation of said general operator.
- 5 34. In a combined typewriting and computing machine, the combination with numeral keys and computing wheels, of members in which numbers are temporarily reg- istered as written, a general operator for carrying numbers from said members into 15 said wheels, a traveling carriage, a denominational selector on said carriage, a jack moved by said denominational selector to obstruct the reading of said wheels, and an extension on said jack acting automatically 20 during a computing operation to cause the operation of said general operator.
